(57) **CLAIM**

The ornamental design for a temporary tattoo cover, as shown and described.

DESCRIPTION

FIG. 1 is a top plan view of a temporary tattoo cover design; FIG. 2 is a bottom plan view of the temporary tattoo cover design of FIG. 1;

FIG. 3 is a left side elevational view of the temporary tattoo cover design of FIG. 1;

FIG. 4 is a right side elevation view of the temporary tattoo cover of FIG. 1;

FIG. 5 is a back elevational view of the temporary tattoo cover design of FIG. 1; and,

FIG. 6 is a front elevational view of the temporary tattoo cover design of FIG. 1.

The broken lines in the figures show structure or boundaries that are not part of the claimed design, but rather show the environment in which the design is associated, or show portions of the article in which the design is embodied or applied to that are not considered part of the claimed design. The horizontal and vertical shading lines indicate opaque surfaces. The oblique shading lines indicate transparent or translucent surfaces.
